HINGE

Enoch Swedman, St. Paul, Minn., assignor to
 Seeger Refrigerator Company, St. Paul, Minn.,
 a corporation of Minnesota

Application May 7, 1945, Serial No. 592,325

4 Claims. (Cl. 16—190)

1

My invention relates to an improvement in hinge, wherein it is desired to provide a simple and effective pivotal support.

In the manufacture of refrigerators there has been a recent trend toward well type cabinets with a horizontal hinged closure. Due to the necessity of insulating such closures and of building them of sturdy construction, these closures are often of considerable size and weight. Accordingly it is desirable to provide a hinge which will act to some extent as a counter-balance for the weight of the closure. At the same time it is necessary that the hinge possess an attractive outward appearance due to the fact that refrigerators are commonly placed in a conspicuous position.

While my hinge is capable of a number of uses, it is the particular object of the present invention to provide a spring hinge which will assist the operation of opening a closure of the type described. This hinge possesses a smooth and attractive outward appearance and yet includes spring means of considerable size and power.

A feature of the present invention resides in the provision of a hinge having two pivotally connected members, one of which is able to telescope into the other. A spring is provided for pulling these parts toward one extreme position, this spring being arranged to partially counter-balance the weight of the closure supported by the hinge.

An important feature of the present invention lies in the provision of a spring hinge connected to a closure which is horizontal in closed position. The hinge is provided with spring means which partially counter-balance the weight of the closure in closed position and which completely counter-balance the weight of the closure in open position so that the closure will remain either in open or in closed position and may be easily operated in any position.

A further feature of the present invention resides in the provision of a hinge including two parts, one of which is connected to the closure and the other of which is designed for attachment to the cabinet. These two hinge parts are pivotally connected together and a spring is also attached to each of the two hinge parts. This spring is attached in such a way that it will move closer to the pivot point as the closure moves into closed position. As the closure is opened the spring moves away from the pivot point between the two parts, thus increasing the leverage of the spring as the spring shortens in length.

2

As a result the increase in leverage due to the shifting of the spring attachment relative to the pivot point more or less compensates for the shortening of the spring. Furthermore, the leverage with which the spring acts upon the closure is at its peak when the closure is in open position, thus holding the closure in open position.

These and other objects and novel features of my invention will be more clearly and fully set forth in the following specification and claims.

In the drawings forming a part of my specification:

Figure 1 is a perspective view of a refrigerator cabinet showing the hinge attached thereto.

Figure 2 is a side elevational view of my hinge with the closure in closed position.

Figure 3 is a view similar to Figure 2 showing the closure in open position.

Figure 4 is a rear elevational view of the hinge.

Figure 5 is a sectional detail through the pivot point of the hinge.

The hinges A are shown attached to the refrigerator cabinet B. Obviously the hinge may be used for various purposes but its use on a refrigerator cabinet is shown and described as the hinge is ideal for such a cabinet.

The refrigerator cabinet B is of the well type including a substantially rectangular body 10 and a closure 11. The closure 11 is pivotally attached to the body 10 by the hinges A and may swing from the horizontal closing position illustrated to the upwardly inclined position which in preferred form is less than ninety degrees from its closed position.

The hinge A includes a main body portion 12 which is secured to the cabinet body 10 by any suitable means such as rivets, bolts, screws or the like, indicated in Figure 1 of the drawings by the numeral 13. The body portion 12 includes a tapered channel-shaped body including a pair of opposed parallel side plates 14 and 15 connected by a channel base 16. The parallel side walls 15 and 14 are wider at their upper extremity than at their lower extremity, thus providing a tapered shell.

Flanges 17 and 19 are connected to the edges of the sides 14 and 15 in opposed relation as illustrated in Figures 1 and 4 of the drawings. These flanges are co-planar and serve as a means of attaching the body 12 to the refrigerator body 10. Apertures 20 are provided in the flanges 17 and 19 through which the anchoring means 13 may extend.

The hinge A also includes a second body mem-

ber 21 which is attached to the cabinet closure 11. The body 21 comprises a sector shaped portion including an arcuated channel base 22 and a pair of segment shaped parallel sides 23 and 24. The sides 23 and 24 are spaced apart a distance proper to closely fit between the parallel body sides 14 and 15. Flanges 25 and 26 extend outwardly from the sides 23 and 24 in opposed relation. These flanges 25 and 26 are either flat or are curved to fit the curvature of the surface of the cabinet to which they are attached. The flanges 25 and 26 are coplanar and include apertures 27 through which attaching means 29 of any suitable type may extend.

In order to pivotally connect the body members 12 and 21 I provide a pivot pin or bolt 30 best illustrated in Figure 5 of the drawings. The pivot pin 30 is supported in apertures 31 in the parallel side plates 14 and 15 and also extends through the sleeve 32 attached to and connecting the parallel side plates 23 and 24 of the body member 21. The two parts 12 and 21 of the hinge are thus free to pivot relative to one another and are so arranged that in closed position of the closure 11 the sector shaped sides 23 and 24 of the body member 21 barely extend into the open upper end of the body portion 12. In open position of the closure 11 the two members 12 and 21 telescope as best illustrated in Figure 3 of the drawings.

A means is provided to limit the relative pivotal movement between the members 12 and 21. In the form illustrated this limiting means comprises a bolt or pin 33 extending between the side plates 14 and 15 of the body member 12. This pin or sleeve 33 is in the path of telescoping movement of the body member 21 and limits pivotal movement thereof. Ears may be bent from the sides 14 and 15 of the member 12 to serve a similar purpose if a less expensive construction is desired.

A bolt or pin 34 connects the side plates 23 and 24 of the body member 21 and a similar bolt or pin 35 extends between the side plates 14 and 15 of the body member 12 near the lower extremity thereof. A spring 36 connects the pins 34 and 35.

An adjustable spring anchor 37 may be provided at one end of the spring 36 if desired so as to change the length of the spring. A suitable anchor 37 may comprise a plug 37a gripped by or secured to, the lower end of the spring 36. Threadedly received by the plug 37a is a hook 38 in engagement with the pin 35. It will be understood that the hook 38 may be screwed inwardly or outwardly to obtain the best adjustment of the spring 36. Normally the adjustment is performed at the factory, and if properly made, requires no further change. However, further adjustment can be made at any time by disengaging the hook 38 from the pin 35, and rotating the hook with respect to the plug 37a.

The operation of my hinge is believed obvious from the foregoing description. The pin 34 is so located that in closed position of the closure 11 the spring 36 is stretched and the axis of the spring is relatively close to the hinge pivot 30. However, in open position of the closure 11 the pin 34 is moved laterally so that the leverage of the spring upon the body member 12 increases. Not only does this arrangement act to increase the effective leverage of the spring as the spring shortens in length but also it provides a maximum leverage against the body member 21 when the closure 11 is in open position. This fact coupled with the fact that the center of gravity of

the closure 11 has moved toward the pivot 30 results in providing a hinge which will hold the door in open position.

It will thus be noted that when the closure 11 is in closed position the spring 36 merely acts as a counter-balance to require less force to open the closure. In open position, however, the cabinet door is retained in place by the spring, allowing the person opening the cabinet to use both hands in inserting into or removing from the cabinet food products.

In accordance with the patent statutes, I have described the principles of construction and operation of my hinge, and while I have endeavored to set forth the best embodiment thereof, I desire to have it understood that obvious changes may be made within the scope of the following claims without departing from the spirit of my invention.

I claim:

1. A hinge for use in conjunction with a cabinet having a substantially vertical panel and a substantially horizontal top closure, the hinge including a channel shaped first hinge body having opposed walls and a connecting wall, means connecting the first hinge body to the vertical wall of the cabinet with that section of the first hinge body opposite the connecting wall being adjacent the cabinet panel, said first hinge body having an open upper end, a second hinge body including a sector shaped portion having a pair of opposed walls and a curved connecting wall, the opposed walls of the second hinge body being in telescopic relation with the opposed walls of the first hinge body, means pivotally connecting the first hinge body to the second hinge body at substantially the center of curvature of said curved wall of the second hinge body, means rigidly connecting one end of said sector shaped portion to said closure, the other end thereof being open, and an elongated spring extending between the opposed walls of both of the hinge bodies and extending from a point near the curved wall to a point near the lower end of the first hinge body.

2. The structure described in claim 1 in which the first hinge body is tapered in form, the opposed sides of the first hinge body being narrower at their lower ends than near their upper ends.

3. The structure described in claim 1 and including a stop extending between the opposed sides of the first hinge body and engageable with an edge of said sector shaped portion of said second hinge body.

4. The structure described in claim 1 and including pins to which said spring is anchored extending between the opposite walls of each of said hinge bodies.

ENOCHE SWEDMAN
